UNITED STATES PATENT OFFICE.

WILLIAM KRAFVE, OF FALL RIVER, MASSACHUSETTS, ASSIGNOR TO CAPITOL MOTORS CORPORATION OF FALL RIVER, MASSACHUSETTS, A CORPORATION OF MASSACHUSETTS.

RADIATOR-SUPPORT.

1,305,810.

Specification of Letters Patent. Patented June 3, 1919.

Application filed June 6, 1918. Serial No. 233,420.

To all whom it may concern:

Be it known that I, WILLIAM KRAFVE, a citizen of the United States, residing at Fall River, in the county of Bristol and State of Massachusetts, have invented a new and useful Improvement in Radiator-Supports, of which the following is a specification.

This invention relates to certain new and useful improvements in radiator supports, and pertains particularly to means for flexibly supporting the radiator from the frame or chassis of an automobile.

The primary object of the invention is to provide a radiator support which will allow the radiator to have movement independent of the chassis or frame so as to thus be relieved from the shocks and jars which the chassis is subjected to.

Further, the invention aims to provide a radiator support which is simple and easily secured in position, and to also provide means for adjusting the support so as to enable the resiliency or flexibility thereof to be governed as desired.

Further and other objects will be later herein set forth and manifested in the course of the following description.

In the drawings—

Figure 1 is a front elevation of the invention showing the frame of the automobile in section, and

Fig. 2 is a section on line 2—2 of Fig. 1.

In proceeding in accordance with the present invention, a strap 1 is employed which may be formed of resilient metal, or which may be a compound textile and rubber strap, or a leather strap, the requirement being strength to support the radiator and a certain degree of flexibility or resiliency.

For the purpose of securing the strap in position, two pairs of clamps 2 are employed, each preferably of L-shape as depicted in the drawings. The horizontal arms of the clamps seat on the opposite faces of the strap and are secured thereto by bolts 3 while the vertical arms of the clamps are secured to the side members F of the frame or chassis by bolts 4, the strap in this manner being supported from each of the opposite horizontal faces thereof.

The radiator R seats on the upper face of the strap and is secured thereto by bolts 5 which latter pass through the strap and through the end parts of a wear and reinforcing strap 6 which abuts the under face

of the strap as depicted in Fig. 1 of the drawings.

Shims or filling plates 7 which are formed of thin metal, back the clamps, at the vertical arms of the latter as illustrated, the plates having apertures to receive the bolts 4 so as to be held in position by the latter. Should the flexible strap 1 increase in length, it is merely thus necessary to remove one or more of the shims, and then secure the clamps in position, to draw the strap 1 taut. Obviously as many of these plates 7 can be used as may be found necessary, the number used being dependent upon the stretch which the strap 1 is possible of.

From the above it will be apparent that the radiator may move independent of the frame or chassis of the vehicle, due to the resilient properties of the supporting medium which holds the radiator. Further, by use of the shims or plates 7 the strap may be made as taut as desired.

Having thus described my invention, what I claim as new and desire to secure by Letters Patent is—

1. In combination with the frame of an automobile, a flexible strap, means to secure the radiator to the strap between the ends of the latter, a pair of substantially L-shape clamps for each end of the strap, said clamps having their horizontal arms engaged with opposite faces of the strap and secured thereto, means to secure the vertical arms of the clamps to the sides of the frame, and a series of shims interposed between said sides of the frame and the vertical arms of the clamps, to allow adjustment of the strap to maintain same taut.

2. In combination with the frame of an automobile, and the radiator thereof, a resilient strap, means to secure the radiator to the strap between the ends of the latter, and means to secure the ends of the strap to the sides of the automobile frame with the strap and its ends in substantially the same plane throughout.

3. In combination with the frame of an automobile and a radiator, flexible means for supporting the radiator, and means for adjustably connecting said flexible means to the frame of the automobile so as to govern the degree of flexibility thereof.

4. In combination with the frame of an automobile and the radiator thereof, a strap formed of resilient material, means to secure

the radiator to the strap, means to secure the strap ends to the automobile frame, and means whereby to enable adjustment of the strap to the desired degree of tautness.

5 5. In combination with the frame of an automobile, a strap, a radiator carried by the strap, a pair of opposed clamps at each end of the strap engaging the respective upper and lower faces thereof, and means to secure 10 the respective clamps to the automobile frame.

6. In combination with the frame of an automobile, and the radiator, a strap of flexible material, means to connect the radiator 15 to the strap so as to be supported by the latter, clamps for securing the strap ends to the automobile frame, and shims between the clamps and the frame for enabling the strap to be adjusted as to being taut.

10 7. In combination with the frame of an

automobile, and the radiator, a strap supporting the radiator, means to connect the strap to the automobile frame and means to adjust said connecting means so as to vary the degree of flexibility of the strap. 25

8. In combination with an automobile frame having a pair of spaced vertical supports, a device connected to each support, means to adjust the devices relatively to their supports, a flexible element connected 30 at its ends to the respective devices, and a radiator supported by said element.

In testimony whereof I have signed my name to this specification in the presence of two subscribing witnesses.

WILLIAM KRAFVE.
